UNITED STATES PATENT OFFICE

2,461,794

SUPPORT FOR ELECTRICAL FIXTURES

Jay E. Williams, Dubuque, Iowa

Application October 2, 1945, Serial No. 619,793

3 Claims. (Cl. 248—57)

1

The instant invention relates to electrical installation and has for its object to provide an adjustable support for boxes, etc.

Another object of the invention is to provide a support having means for biting into opposing studs.

A further object of this invention is to provide an expansible support for an electrical fixture.

A still further object of the invention is to provide a support which may be installed without removing flooring or wall for installation thereof.

Other features and advantages will become more readily apparent from the following description and the accompanying illustrative drawings in which:

Figure 1 is a diagrammatic view illustrating the application of my invention.

Figure 2 is a longitudinal sectional view of my support.

Figure 3 is a transverse sectional view thereof.

Figure 4 is a detail enlarged of one end of the device, and

Figure 5 is a detail longitudinal sectional view of the reverse end thereof.

In the above drawings as well as in the specification to follow, the same characters of reference indicate the same parts throughout.

While one embodiment of my invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of my device, which is to be limited only in accordance with the appended claims. And while I have stated the primary field of utility of my invention it remains obvious that it may be employed in any other capacity wherein it may be found applicable.

In the drawings forming a part of this application 10 indicates my invention which consists of a tube 11, the bore at the end 12 thereof being reduced in diameter and screw-threaded as at 13. Threaded into the tube 11 is a long rod 14 threaded throughout its length as at 15. The outer terminal 16 of rod 14 is reduced to a substantially needle point 17. The end 18 of tube 11 is provided with sharp edge 18'.

Slidably adjustable and frictionally supported on the tube 11 is a collar 19 provided with a tubular stud or hickey 20, the threading 21 of

2

which is adapted to receive the nut 22 after the stud or hickey has been projected through the inner wall 23 of a switch or other electrical appliance box 24. The stud 20 has a bore 25 extending to the reduced threaded bore 26 extending to and through the collar 19, whereby after the collar has been adjusted upon the tube 11 to align with the box opening 27 in a wall or floor 28, a set screw 29 may be tightened up against the tube 11 thus securing the member 19 in place.

The above described support and box retainer may be projected longitudinally through the box opening 27 as indicated in Figure 1 of the drawings and the tube 11 rotated by hand until the part 17 and edge 18' project far enough into the studding 30 and 31 sufficiently to hold its position, then a pipe wrench is applied to rotate the tube 11 enough to cause the said point and teeth to penetrate far enough into the studding for permanent connection therewith. Now the collar 19 may be shifted to a desired position and the screw 29 tightened. The device may as readily be removed when necessary.

From the foregoing description it will be obvious that I have provided a support which may be applied and adjusted for connection with a box 24 in about a minute and that the box 24 may be rigidly and securely connected thereto.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention that which I claim as new and desire to procure by Letters Patent is:

1. A positioning means for fixture supporting bars comprising an elongated tube having stud engaging and penetrating teeth on one end and a threaded bearing formed in its opposite end, an elongated threaded stud engaging bar adjustably received in the tube and actuated by the threaded bearing in said tube said bar having a stud engaging and penetrating tooth at its outer end, a one-piece combination sleeve and externally threaded hollow hickey adjustably received on said tube, and a locking bolt disposed in said hollow hickey extending through said sleeve for engaging said tube for locking the hickey in the desired adjusted position.

2. A positioning means for fixture supporting bars comprising an elongated threaded rod having a stud penetrating tooth at one end thereof, an actuating tube received around the rod and having stud engaging and penetrating teeth at one end thereof, means formed in said tube for selectively moving said rod in and out of the tube to advance the toothed end thereof into a stud, a sleeve adjustably received on the tube, an externally threaded hollow hickey depending integrally from said sleeve, a locking bolt disposed in said hollow hickey and extending through said sleeve for engaging said tube and locking the hickey in the desired adjusted position.

3. The combination of claim 2, wherein said

means includes a substantially closed end in said tube, a longitudinally internally threaded bore in said closed end for receiving the threaded rod, whereby rotation of the tube correspondingly actuates the rod.

JAY E. WILLIAMS.
